UNITED STATES PATENT OFFICE.

LON T. HARRIGAN, OF SAN QUENTIN, CALIFORNIA, ASSIGNOR, BY MESNE ASSIGNMENTS, TO HYDRO PATENTS COMPANY, A CORPORATION OF CALIFORNIA.

AUTOMATIC BRAKE-CONTROL MECHANISM FOR AUTOMOBILES.

Application filed May 5, 1923. Serial No. 637,001.

To all whom it may concern:

Be it known that I, LON T. HARRIGAN, a citizen of the United States, residing at San Quentin, in the county of Marin and State 5 of California, have invented new and useful Improvements in Automatic Brake-Control Mechanism for Automobiles, of which the following is a specification.

This invention relates to an automatic 10 brake control mechanism for automobiles.

The principal object of this invention is to provide means whereby the brakes of an automobile will be automatically applied when the drive shaft rotates faster than a 15 predetermined speed.

Another object is to provide a mechanism of this character which may be applied to any vehicle now upon the market without materially altering the construction of the 20 same.

Another object is to produce a device of this character which is simple in construction, and therefore cheap to manufacture.

A still further object of this invention 25 is to provide a device which will be automatic in its operation and one which will require a minimum amount of care.

Other objects and advantages will be apparent during the course of the following 30 description.

In the accompanying drawings forming a part of this specification, and in which like numerals are employed to designate like parts throughout the same.

Figure 1 is a side elevation of my device, 35 Figure 2 is a cross section taken on the lines 2—2 of Figure 3,

Figure 3 is a cross section taken on the line 3—3 of Figure 2.

Applicant is aware of the fact that governors have been employed for the purpose 40 of regulating the speed of an engine. These devices, however, are inefficient as it is often necessary to run the engine at a higher 45 speed than the governor is set for as for instance when climbing hill in low gear.

I have therefore devised means whereby 50 the brakes will be automatically applied whenever the drive shaft revolves at a speed beyond a predetermined amount.

In the accompanying drawings wherein 55 for the purpose of illustration is shown a preferred embodiment of my invention, the numeral 5 designates a cylinder closed by a

threaded head 6 and having a stuffing box 55 7 at its opposite end.

A piston rod 8 extends through the stuffing box 7 and has a piston 9 secured thereto. This piston rod has a slot 11 formed upon its free extremity within which a cross piece 60 12 is adapted to ride. This cross piece is secured to the ordinary brake rod 13 of the automobile.

Lugs 14 and 16 are formed integral with the cylinder 5 so that the same may be suspended beneath the floor of the vehicle. 65 The cylinder 5 is provided with a port 17 and a port 18, which ports are positioned upon opposite sides of the piston 9. It will be observed that the port 17 has a nipple 15 70 secured therein which nipple is connected to a union 18, which is in turn connected to a pipe 19.

One end of this pipe enters a pump casing 21, while the opposite end is connected 75 to a valve casting 22. The port 18 has a similar nipple 23 secured therein, which nipple is connected to a union 24 from which a pipe 26 leads to the bottom of the pump casing 21. 80

A branch pipe 27 connects the pipe 26 to the bottom of the valve casting 22. A bracket 28 serves to support the pump casing at a suitable point beneath the cylinder 5, while a bracket 29 supports the pipe 19. 85 Positioned between the pump casing 21 and the valve casting 22 is a housing 31, within which is located a governor 32 of the centrifugal ball type, which governor is rotated through the medium of a shaft 33 extending 90 through the pump casing and having a driving sprocket 34 secured to its opposite end. It is of course understood that pumping rotors as shown at 36 and 37 are mounted within the pump casing and function in the 95 usual manner one of these rotors being secured to the shaft 33 so as to be driven thereby. The numeral 38 designates a chain which extends from the sprocket 34 to a sprocket mounted upon the driving shaft 100 39 of the vehicle, while the numeral 41 designates a valve provided with a valve stem 42 connected to the governor 32, which valve under normal conditions is adapted to be out of contact with a valve seat 43.

The operation of my device is as follows:— 105 Assuming that the vehicle is traveling

upon the road, the drive shaft 39 will be revolving, which will transmit motion through the chain 38. This action will cause the governor 32 to rotate and when the speed of rotation of the governor has become sufficient to overcome the spring tension for which it has been set, the balls will fly out and cause the valve 41 to move toward its seat 43. During this time the fluid within the pipe 19 has been circulating through the pump, and will next be discharged into the pipe 26, and thence through the pipe 27, valve casting 22 and back to the pump 19. As soon, however, as the valve comes into contact with its seat this circulation can not take place, and thus the fluid will flow through the pipe 26 through the port 18 and cause the piston 9 to move in the direction of the arrow. While the fluid in front of the piston will be transferred to the back thereof, through the medium of the pump, thus drawing fluid from the port 17. As the said piston moves outwardly the rod 8 will contact the cross piece 12 and thereby move the brake rod in a direction which will apply the brakes. When the speed has been slackened the governor will automatically open the valve and thereby allow the normal circulation to again take place, with the result that the car will function in the usual manner.

It is to be understood that the form of my invention herewith shown and described is to be taken as a preferred example of the same and that various changes in the shape, size and arrangement of parts may be resorted to without departing from the spirit of the invention or the scope of the subjoined claims.

Having thus described my invention, I claim:—

1. In combination with an automobile hav-

ing a brake rod and a driven shaft, of a fluid containing cylinder mounted adjacent thereto, a piston mounted within said cylinder, a connection between the piston rod and the brake rod permitting a limited manually applied braking movement of the brake rod independent of the piston rod, a shaft mounted below said cylinder, means for driving said last mentioned shaft from the driven shaft, a governor mounted upon said second mentioned shaft, and a valve controlled by said governor for regulating the flow of fluid from one side of said piston to the opposite side thereof.

2. In a motor vehicle, a brake, driving means between the motor and traction wheels, a dual control for the brake comprising a manually operated brake rod and a fluid pressure mechanism, the fluid pressure mechanism being connected to the brake rod and responsive to the speed of the said driving means, said connection between the fluid pressure mechanism and the brake rod permitting the brake rod to be manually actuated independently of the fluid pressure mechanism.

3. In a motor vehicle, a brake, an actuating rod therefor, manually manipulated means for actuating the brake by said rod, a fluid brake applying means, including a cylinder having a piston therein, a rod for said piston, an elongated slot in the piston rod, means fixed to the brake rod and connected to the piston rod with a limited longitudinal movement in said slot, the manually manipulated means for actuating the brake being operable independently of the fluid brake applying means with the movement of the brake rod limited to the length of the slot in the piston rod.

In testimony whereof I affix my signature.
LON T. HARRIGAN.
